BACK PANEL FOR A LAUNDRY APPLIANCE

Charles D. Dushek, Lisle, Ill., assignor to General Electric Company, a corporation of New York

Filed July 13, 1960, Ser. No. 61,345

Term of patent 7 years

(Cl. D49—1)

FIG. 2

FIG. 1 is a front perspective view of a back panel for a laundry appliance showing my new design; and FIG. 2 is a side elevational view thereof.

The dominant features of the design reside in the portion shown in full lines.

The side of the panel not shown and the rear thereof are substantially plain.

What is claimed is:

The ornamental design for a back panel for a laundry appliance, substantially as shown and described.
